Primary Examiner — Ruth McInroy(74) *Attorney, Agent, or Firm* — Sheppard Mullin Richter & Hampton, LLP**CLAIM**

We claim the ornamental design for a grill, as shown and described.

DESCRIPTION

FIG. 1 is a perspective view of the grill showing the new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof.
